UNITED STATES PATENT OFFICE.

ELIAS H. COWART, OF SAN FRANCISCO, CALIFORNIA.

STEERING-GEAR FOR VEHICLES.

SPECIFICATION forming part of Letters Patent No. 672,075, dated April 16, 1901.

Application filed April 5, 1900. Serial No. 11,771. (No model.)

To all whom it may concern:

Be it known that I, ELIAS H. COWART, a citizen of the United States, residing at San Francisco, in the county of San Francisco and State of California, have invented certain new and useful Improvements in Steering-Gear for Vehicles; and I do hereby declare the following to be a full, clear, and exact description of the invention, such as will enable others skilled in the art to which it appertains to make and use the same.

My present invention relates to certain improvements in steering-gear for vehicles; and it has for its objects, among others, to provide an improved construction in which provision is made for the unisonous pivotal play of both forward and rear axles without the employment of the usually-positioned pivoted cross-reaches.

In deriving the above prime results, and with the additional aim of preserving the steadiness of the vehicle, I have provided novel details, whose objects and advantages will appear in the matter hereinafter set forth.

The objects of my invention I am enabled to accomplish by the means illustrated in the accompanying drawings, in which—

Figure 1 is a top view of the running-gear of an ordinary farm-wagon with the bed and bolsters removed in order to show the relative arrangement of my invention. Fig. 2 is an enlarged top view of the main portion of my invention. Fig. 3 is a section on the line xx of Fig. 2. Fig. 4 is a section on the line yy of Fig. 2.

I will now explain in detail the construction and operation of my invention, reference being had to the above views by numerals.

The running-gear of the wagon consists, essentially, of the four wheels 1, of equal diameters, mounted on the forward and rear axles 2 and 3, respectively.

Secured centrally to the forward axle 2 and reaching backward therefrom to within a short distance of a point midway between the two axles is the forward coupling-pole or reach 4, while similarly positioned to the rear axle 3 and braced thereto by means of the rear hounds 5 is the hind reach 6. Now in order to pivotally connect the abutting ends of the reaches 4 and 6 and at the same time permit of the forward and rear axles swinging in unison

in opposite directions I have constructed the mechanism shown in Figs. 2, 3, and 4. Protruding outward from the upper and lower surfaces of the free ends of the forward and hind reaches 4 and 6 and securely bolted thereto are the plates 7 and 8, respectively, the former overlapping the latter. Passing through a perforation in these plates 7 and 8 through longitudinal slots 9 in the plates 8 is the pin 10, while held in place by the pin 10 and interposed between the plates 7 is the member 11, which is formed with the upper and lower guides 12, adapted to engage with the slots 9.

It will be readily seen from the description so far gone into that by swinging the pole 13 in either direction the forward axle and wheels will be thrown in a like manner, and consequently the rear axle and wheels in the opposite direction, the latter being the result of the connection between the forward and hind reaches just described. Now as this swinging action takes place there must be some allowance made for the increased distance taken on the line of the reaches, and this I provide for by means of the slots 9, which permit of the desired longitudinal play between the plates 8 and member 11.

It will be quite evident that in the usual motion of the wagon straight ahead if I did not provide some means for keeping the forward and rear reaches 4 and 6 rigidly in a straight line every irregularity in the road would cause the hind axle to jerk from side to side and produce a very unsteady motion of the vehicle. Now in order to prevent the unsteady motion just referred to I have provided the latches 14 and 15, which engage with notches 17 on opposite sides of the member 11 and are held therein by means of the springs 18. In order to disengage these springs 18 as the pole is turned, I have positioned the pins 19 on the forward hounds 20. It is manifest that as the pole is turned in either direction either one or the other of the pins 19 will throw the latch 14 or 15 out of engagement with the notch 17, thereby allowing the member to turn freely into either the position shown in dotted lines or that shown in broken lines in Fig. 1.

Of course the load on the hind bolster and axle cannot be made dependent on the jointed

reaches to draw, and consequently I have provided the rod 21, which joins the forward and hind king-bolts 22 and 23. This rod I have made adjustable by means of the turnbuckle 5 24, while in order not to cover up in the drawings the other mechanism of my invention I have broken off the central portion of the rod, as shown in Fig. 1.

The construction and arrangement of the 10 several parts of my invention being thus made known, the operation and advantages of the same will, it is thought, be readily understood.

What I claim, and desire to secure by Letters Patent, is—

15 1. In combination with the forward and rear axles of a vehicle, an independent reach secured to each of said axles, said reaches being joined together by means of a longitudinally-playing connection, and means for lock-

ing said reaches together in a straight line to 20 prevent the accidental swinging of said axles, said axles being centrally pivoted, substantially as and for the purpose set forth.

2. A vehicle having forward and rear pivoted axles connected by a central-jointed 25 reach, suitable latches for locking said reaches and preventing the action of said joint, said joint being provided for longitudinal as well as pivotal play, and means for releasing said locking-latches, substantially 30 as set forth.

In testimony whereof I affix my signature in presence of two witnesses.

ELIAS H. COWART.
